[57] CLAIM

The ornamental design for a garden arbor, as shown and described.

DESCRIPTION

FIG. 1 is a perspective view of the garden arbor showing my new design;

FIG. 2 is a side elevational view thereof, the opposite side comprising a mirror image of the side shown in FIG. 2;

FIG. 3 is a top plan view;

FIG. 4 is a front elevational view, a rear elevational view of the arbor comprising a mirror image of the front; and

FIG. 5 is a bottom plan view.

FIG. 1

FIG. 2

FIG. 3

FIG. 4
